United States Patent

Des. 239,809
Patented May 11, 1976

239,809

COMPARTMENTED PLATE

Theodore E. Miller, 3715 Annabelle St.,
Detroit, Mich. 48217

Filed Oct. 9, 1973, Ser. No. 404,666

Term of patent 14 years

Int. Cl. D7—01

U.S. Cl. D7—27

FIG. 1 is a top plan view of a compartmented plate embodying my new design.

FIG. 2 is a side elevational view thereof.

FIG. 3 is a cross-sectional view taken along the lines 3—3 of FIG. 1.

The bottom of the compartmented plate embodying my design as shown in FIGS. 1-3 is plane and unornamented.

I claim:

The ornamental design for a compartmented plate, as shown and described.
